UNITED STATES PATENT OFFICE.

PERCY D. BECK, OF LAWRENCE, KANSAS.

DESIGN FOR A TIRE-TREAD.

51,544.

Specification for Design. Patented Dec. 11, 1917.

Application filed October 16, 1917. Serial No. 196,963. Term of patent 3½ years.

To all whom it may concern:

Be it known that I, PERCY D. BECK, a citizen of the United States, residing at Lawrence, in the county of Douglas and State of Kansas, have invented a new original Design for Tire-Treads, of which the following is a specification, reference being had to the accompanying drawings, forming part thereof.

The figure is a plan view of a section of the tire showing my new design.

I claim:

The design for a tire tread, as shown.

PERCY D. BECK.
